[57] ABSTRACT

Photographic apparatus including film-advancing structure for asymmetrically engaging a film unit and moving it into engagement with a pair of pressure-applying members. The pressure-applying members are adapted to rupture a container of processing composition located near one end of the film unit and spread the contents thereof across a photosensitive layer of the film unit to initiate formation of a visible image. The asymmetrical engagement of the film unit by the film-advancing structure may result in the film unit being slightly canted as it moves into engagement with the pressure-applying members. Advancing the canted film unit between the pressure-applying members may result in an incomplete spread of the processing composition, i.e., some portion of the photosensitive layer will not be covered by the processing composition. This condition is substantially obviated by providing the pressure-applying members with the facility to spread the processing composition across the photosensitive layer in a layer having an asymmetrical thickness, as measured in a direction transverse to the direction of movement of the film unit through the pressure-applying members.

PHOTOGRAPHIC APPARATUS

CROSS REFERENCE TO RELATED APPLICATION

This application is in part a continuation of my co-pending application Ser. No. 299,669, filed Oct. 24, 1972 now abandoned.

BACKGROUND OF THE INVENTION

1. Field of the Invention

This invention relates to photographic apparatus of the type adapted to spread a processing composition across an exposed photosensitive layer.

2. Description of the Prior Art

Photographic apparatus of the self-developing type are well known in the art and generally include film-advancing means for engaging and moving an exposed film unit out of its exposure position and into engagement with a pair of pressure-applying members, e.g., rollers. The film unit includes a pod, or container, of processing composition, e.g., liquid, having a sealed, rearwardly facing discharge end which is parallel with and adjacent to a leading end of the film unit. The rollers are adapted to engage the leading end of the film unit and the pod to generate sufficient pressure within the processing composition to rupture the seal and spread the contents thereof across a photosensitive layer of the film unit to initiate formation of a visible image within the film unit while simultaneously advancing the film unit to a viewing station.

Generally, the film-advancing means is constructed and positioned such that the film unit is not canted as it moves into engagement with the bite of the rollers, i.e., the leading end of the film unit is generally parallel with the axes of the rollers thereby enabling the rollers to maximize the spread of the processing composition across the photosensitive layer of the film unit. Obviously, this criterion severely restricts the designer's choice and arrangement of the film-advancing means. Therefore, there is a need for a camera of the self-developing type wherein the film unit may be advanced in a canted orientation between the pressure-applying members without adversely affecting the quality of the spread of processing composition across the photosensitive layer.

SUMMARY OF THE INVENTION

The instant invention relates to photographic apparatus and, more particularly, to pressure-applying means for spreading a processing composition across an exposed photosensitive layer to initiate formation of a visible image. According to the instant invention, the pressure-applying means is especially adapted for use with cameras of the type having film-advancing means which apply a force to an exposed film unit along a line which tends to cant or skew the film unit as it is moved out of its exposure position and into engagement with the pressure-applying means. Ordinarily, orienting the film unit in a skewed manner prior to its entry between the pressure-applying means will increase the possibility that the contents of the pod of processing composition located adjacent the leading end of the exposed film unit will not be spread over the entire area of the film unit's photosensitive layer thereby resulting in a portion of the photographed scene not being processed into a visible image. For example, if the film unit were

skewed a few degrees as it enters the bite of the pressure-applying means, the processing composition contained within the pod would not only be spread from the front of the film unit to the rear but it, the composition, would also have a tendency to move laterally toward one side of the film unit because of the angle between the pressure-applying means and the discharge end(s) of the pod(s). Movement of the processing composition toward the one side of the film unit and away from the other side thereof during front to rear spreading may result in a spread which does not cover the rear corner of the other side of the film unit. This problem is substantially obviated by spreading the process composition on the other side of the film unit in a thinner layer than on the one side thereby spreading the available processing composition on the other side over a greater area before it becomes depleted. This is accomplished, in a preferred embodiment, by providing the camera with pressure-applying means, e.g., a pair of rollers, which are adapted to spread the processing composition across the film unit in a layer having an asymmetrical thickness as measured transversely of the film unit with the minimum depth of the layer being located on that side of the film unit where incomplete coverage of the photosensitive area by the composition is most likely to occur.

One of the rollers, preferably the bottom roller, has a generally symmetrical longitudinal cross section including opposite end portions which are adapted to engage longitudinally extending binding elements of a film unit. The other roller, i.e., the top roller, includes collars at each end thereof which are adapted to engage the ends of the bottom roller for providing a gap of predetermined minimum depth therebetween to facilitate entry of the film unit. The top roller also includes an intermediate film unit engaging portion having a length slightly less than the lateral distance between the binding elements and film unit engaging end portions located between each end of the intermediate portion and the collars. The aforementioned end portions of the top roller are adapted to cooperate with the opposite end portions of the bottom roller to engage the binding elements of the film unit as it passes therebetween to define the depth of the layer of processing composition to be spread across the photosensitive layer.

As stated above, if the exposed film unit enters the bite of the rollers in a canted orientation, a portion of the photosensitive layer of the film unit may not be covered by the layer of processing composition. To provide for this contingency, one of the end portions of the top roller is provided with a smaller diameter than the other end portion of the top roller, thus resulting in the longitudinally extending asymmetrically configured gap between the rollers when a film unit is passing therebetween. Also, the end portion of the top roller having the reduced diameter is located on the side of the roller assembly which first receives a portion of the leading end of the canted or skewed film unit because, it is usually the rear corner of the film unit located on the same side of the longitudinal axis of the film unit as that portion which first enters the bite of the rollers where the aforementioned incomplete coverage of the photosensitive layer will occur. The asymmetrically configured gap between the rollers, which is a result of reducing the diameter of one of the end portions of the top roller, provides a structure wherein the depth of the

layer of processing composition is thinner on that side of the film unit which first enters the bite of the rollers than on the other side of the film unit, i.e., the rollers spread the processing composition across the photosensitive layer of the film unit in a layer having an asymmetrical thickness, as measured in a direction transverse to the direction of movement of the film unit relative to the rollers. By spreading the processing composition in a thinner layer on the side of the film unit where the incomplete coverage is most likely to occur, the processing composition originally available on that side of the film unit is spread over a greater area of the photosensitive layer before the composition becomes depleted.

In an alternative embodiment, the pressure-applying means preferably include a pair of rollers which define a gap through which an exposed film unit is adapted to be moved, and a torsion spring the opposite ends of which are adapted to engage opposite ends of one of the rollers for resiliently biasing it toward the other roller. The ends of the torsion spring are bent at different angles such that when the pressure-applying means is assembled, one end of the torsion spring will apply a greater force to one end of the roller than the other end, thereby asymmetrically loading the roller. When a film unit is located between the rollers, the asymmetric loading produces an elongated asymmetrically configured gap between the rollers with the depth of the gap toward the end having the greater force being less than that at the other end, to produce a layer of processing composition having an asymmetrical thickness. The end of the roller having the greatest biasing force is adapted to spread the processing composition in a thinner layer across that side of the film unit where the aforementioned incomplete spread is most likely to occur, thereby insuring complete coverage of the photosensitive area of the film unit.

In still another embodiment, the pressure-applying means preferably include a pair of juxtaposed rollers which cooperate with each other to define a gap having an asymmetrical configuration. One of the rollers, preferably the upper roller, has a substantially uniform diameter throughout a major portion thereof while the other roller has a substantially "candlepin" configuration, i.e., its diameter gradually decreases from a maximum diameter intermediate its ends to a minimum diameter at or near its opposite ends. The configuration of the other roller is also asymmetrical in that its major diameter is closer to one end of the roller than the other end, and more specifically, is located closer to the end of the roller assembly which first receives a leading end portion of an exposed film unit. As in the embodiments previously described, offsetting the maximum diameter of the roller towards the side of the roller assembly which first receives the film unit results in an asymmetrical spread of the processing composition, i.e., the processing composition is spread in a thinner layer across that side of the film unit where the incomplete spread is most likely to occur than across the other side.

An object of the invention is to provide photographic apparatus for spreading a processing composition across a photosensitive area of an exposed film unit in a layer having an asymmetrical thickness.

Another object of the invention is to provide a camera of the self-developing type with pressure-applying means having a longitudinally extending, asymmetrically

configured gap for spreading a processing composition across a photosensitive layer of an exposed film unit as it is being advanced therethrough.

Another object of the invention is to provide pressure-applying means including a first member having a longitudinally extending, asymmetrically configured surface defining one portion of a gap and a second member having a longitudinally extending, symmetrically configured portion defining a second portion of a gap.

Another object of the invention is to asymmetrically bias at least one of a pair of pressure-applying members to provide a spread of processing composition of non-uniform thickness.

Still another object of the invention is to provide photographic apparatus of the type having means for engaging a film unit near one side thereof and moving the film unit out of an exposure position, with means for asymmetrically spreading a processing composition across the film unit in a layer of non-uniform thickness.

Still another object of the invention is to provide a spreading assembly for spreading a processing composition across substantially the entire photosensitive area of an exposed film unit which was originally moved into engagement with the spreading assembly in a skewed or canted condition.

Other objects of the invention will in part be obvious and will in part appear hereinafter.

The invention accordingly comprises the apparatus possessing the construction, combination of elements and arrangement of parts which are exemplified in the following detailed disclosure, and the scope of the application of which will be indicated in the claims.

BRIEF DESCRIPTION OF THE DRAWINGS

For a fuller understanding of the nature and objects of the invention, reference should be had to the following detailed description taken in connection with the accompanying drawings wherein:

FIG. 1 is a perspective view, partly in section, of photographic apparatus embodying the instant invention;

FIG. 2 is an exploded perspective view of a preferred form of spreading assembly;

FIG. 2a is an enlarged view of one end of one of the rollers shown in FIG. 2;

FIG. 3 is a diagrammatic plan view of a skewed or canted film unit about to engage a spreading assembly;

FIG. 4 is a diagrammatic end view of a film unit passing between the spread rollers of the assembly shown in FIG. 2;

FIG. 5 is a diagrammatic end view of a film unit passing between a pair of asymmetrically biased spread rollers; and

FIG. 6 is a diagrammatic end view of a film unit passing between a pair of spread rollers of an alternative embodiment of the invention.

DETAILED DESCRIPTION OF THE INVENTION

Reference is now made to FIG. 1 of the drawings wherein is shown photographic apparatus in the form of a selfdeveloping camera 10. Camera 10 includes an exposure chamber 12 defined by housing sections 14, 16, 18 and 20 and an expansible bellows 22 (only one side being shown). Housing section 14 includes a lens

and shutter assembly 24, a photocell 26 and an exposure initiating button 28. Mounted on top of housing section 16 is a viewfinder 30. Housing sections 14, 16, 18 and 20 and viewfinder 30 are pivotally coupled for movement between the extended operative position shown in FIG. 1 and a compact folded position, as is more fully described in U.S. Pat. No. 3,678,831.

Exposure chamber 12 is adapted to receive a film cassette 32 having an exposure aperture 34 in a forward wall 36, a resilient member 37 extending part way across an exit opening 38 in one end wall to prevent the passage of more than one film unit at a time therethrough and an elongated opening 40 in wall 36 which extends to the rear (to the left) of the cassette and part way down the rear end wall of the cassette. Positioned within cassette 32 are a plurality of film units 42 (see FIG. 3) which may be of the type shown in U.S. Pat. No. 3,415,644. Each film unit 42 includes a leading end 44 having a container or pod 46 containing a processing composition 47 attached thereto, superposed image-receiving and photosensitive layers positioned in alignment with opening 38, and a trailing end 50.

Camera 10 further includes a motor 52 which may be powered by a battery located within cassette 32, a gear train 54 for operating various components of the camera including film-advancing means 56 having a cantilevered mounted film engaging member 58, pressure-applying means including a pair of pressure-applying members or rollers 60 and 62 drivingly coupled to the gear train 54 via gear 64, and an elongated member 66 for assisting in the movement of a pivotally mounted reflecting assembly 68.

Reflecting assembly 68 includes a support 70 having a planar mirror 72 mounted on one side thereof and an echelon type reflecting surface 74 on the other side. As is more fully described in U.S. Pat. No. 3,678,831, reflecting assembly 68 is adapted to be pivoted between an exposure position adjacent a mirror 76 located on housing section 18 wherein light from lens 24 is reflected by mirror 72 to expose the uppermost film unit located in position for exposure, and a viewing position closely adjacent cassette 32 wherein echelon surface 74 cooperates with lens 24, mirror 76 and viewing device 30 to provide the photographer with a single lens reflex viewing and focusing system. For a more detailed description of the operation of the camera, reference is made to the copending application Ser. No. 171,127, filed Aug. 12, 1971 by Edwin H. Land and now U.S. Pat. No. 3,753,392, and to U.S. Pat. No. 3,714,879, granted to Land et al., on Feb. 6, 1973, both of which are assigned in common herewith.

As indicated, the present invention is particularly directed to certain aspects of the camer's spreading assembly, the nature of which may best be understood by now referring to FIG. 2 of the drawings. As shown therein, the assembly comprises a spread roll bracket 80 preferably formed from a unitary piece of sheet metal such as a stainless or carbon steel. Bracket 80 includes a pair of upturned ears 82 and 84 joined together by a central portion 86 comprising a support 88 and spaced apart substantially parallel flange portions 90 and 92. A rigid structural support member 94 is configured to seat against the support 88 intermediate the ears 82 and 84 and nested between the flange portions 90 and 92 of the bracket 80. A pair of rivets 95 serve to secure the support member 94 to the bracket 80. A specially configured torsion spring 96 rests in tracks 98

of the support member 94 with a generally U-shaped central portion 100 thereof extending around a lip 102 formed on the support member and seated against a supporting surface 104 of that member. When the spring 96 is positioned on the support member 94 and the support member connected to the bracket 80 as indicated, an elongated projection 106 depending from the bracket's flange portion 92 serves to retain the spring in position on the support member. In this manner, the main body of the spring 96 is unexposed, i.e., retained within the confines of the bracket 80.

Roller 60, which is preferably of a symmetrical "candlepin" configuration, but may be cylindrical, has its major axis located equidistant between its ends and uniformly tapers down to similar minor diameters at its ends. For example, in a spread roller assembly where roller 62 has a diameter of .250 inches throughout its intermediate sheet contacting surface, roller 60 may have a major diameter of .2533 inches at the point equidistant from the ends and minor diameters of .250 inches at its ends. Also, roller 60 is hollow and therefore relatively light in weight and of low inertia, being rotatably mounted on a shaft 108 by a pair of ball bearing assemblies 110. Opposite ends of the shaft 108 extend through elongated slots 112 and 114 provided in the ears 82 and 84 of the bracket 80. Flattened ends 116 and 118 of the torsion spring 96 seat in appropriately positioned annular recesses 120 of the shaft 108 so that the force of that spring continually urges the roller 60 towards its upwardmost position within the slots 112 and 114 as viewed in FIG. 2. It will be noted that the support member 94 is configured with a pair of cutouts 121 to accommodate initial loading of the spring 96 and subsequent displacement of its flattened ends 116 and 118 responsive to translatory movement of the shaft 108 along the bracket's slots 112 and 114.

Extensions 122 of the roller 62 are respectively journaled to the bracket 80 by ball bearing assemblies 124 mounted in the bracket's ears 82 and 84. Provided on the roller 62 are a pair of spaced apart annular collars 126 against which the roller 60 is initially seated under the force of the torsion spring 96. These collars 126 determine a controlled minimum gap between the sheet-contacting facing surfaces 128 and 130 of the rollers 60 and 62 which facilitates the initial introduction of a film unit therebetween. As the film unit 42 is introduced between the rollers 60 and 62 (see FIG. 4) it effects a displacement of the roller 60 away from the roller 62 against the force exerted on the roller 60 by the torsion spring 96. As the exposed film unit 42 is advanced between the rollers 60 and 62, the compressive force exerted thereon by same effects a spreading of the processing composition from pod 46 in a layer across the photosensitive layer of the film unit. Preferably, the roller 62 is provided with a pair of spaced apart annular recesses 132 strategically positioned as shown to receive selected portions of specially configured longitudinal edge bindings 134 of the film unit 42 in order to preclude the "red-framing" effect in accordance with the teachings of U.S. Pat. No. 3,647,441 by Albert J. Bachelder entitled PHOTOGRAPHIC APPARATUS AND METHOD, issued on Mar. 7, 1972.

In this unique arrangement, any frictional forces in the roller 60 — shaft 108 assembly resulting from twisting or cocking of the bearing assemblies 110 are absorbed by the shaft 108 which is basically a non-rotating component. Thus, such frictional forces are

not transmitted from that assembly back to the battery thereby reducing the load on that energy source. Most significantly, frictional forces of the roller assembly have been minimized by providing an arrangement wherein there is a non-rotating contact between the ends 116 and 118 of spring 96 and the shaft 108.

OPERATION

After the photographer has focused the scene through the viewfinder 30, button 28 is depressed to initiate an exposure cycle. Subsequent to actuation of button 28, exposure chamber 12 is made lighttight by closing shutter 24 and the viewfinder's entrance pupil 111. Motor 52 is energized to move reflecting assembly 68 to the up or exposure position. Motor 52 is then stopped and the shutter opened and closed to expose the forwardmost film unit 42 in cassette 32. Motor 52 is again started to drive gear train 54 to move member 66 to the left, as viewed in FIG. 1, thereby returning reflecting assembly 68 to the viewing position and to actuate film-advancing means 56. Actuation of the film-advancing means moves the film engaging member 58 into contact with the trailing edge 50 of film unit 42 to move the film unit out of its exposure position and into the bite of the rotating rollers 60 and 62 via exit opening 38 in cassette 32. It should be noted that the film engaging member 56 engages the film unit on one side of its longitudinal axis, indicated as 115 in FIG. 3. Engaging and moving a film unit in this manner may result in the film unit being canted as it is about to enter the bite of rollers 60 and 62 as shown in FIG. 3. Canting of the film unit 42 is possible because usually its width is slightly less than the width of the interior of cassette 32. Should the film unit enter the bite of rollers 60 and 62 in a canted condition, a spread pattern similar to that shown by the lines 140, 142, 144, 146, 148, 150 and 152 in FIG. 3 may be produced. These lines represent progressive stages of the advancing edge of the processing composition during spreading of the composition. For example, where pod 46 is comprised of three segments, as shown in FIG. 3, initial rupturing of the pod 46 by rollers 60 and 62 presents an advancing wave front as shown at 140. As the film unit continues to move through the rollers 60 and 62 the major portion of the wave front progressively flattens out while the left side of the wave trails behind, as shown from 146 through 150. However, the processing composition is not only spread from the leading end of the film unit to its trailing end 50 but also from the left side (as viewed in FIG. 3) of the film unit to the right side, i.e., there is a lateral movement of the processing composition to the right. This lateral movement of the processing composition may be caused by a lateral force component created as a result of the acute angle between a line containing the discharge end 49 of pod 46, which is perpendicular to the longitudinal axis 115, and a plane containing the longitudinal axes of the rollers. Lateral movement of the processing composition to the right may result in the left side of the wave receding relative to the remainder of the wave front until you reach a condition as shown at 152 where substantially the entire photosensitive area of the film unit has been covered with processing composition except for area 153. In other words, it appears that the amount of composition originally provided for covering the left half of the film unit is gradually reduced by the movement of the composition from the left side of the film unit to the

right side thereby resulting in the composition on the left side being depleted before the corner area 153 of the film unit has been covered by the processing composition. Obviously, this type of a spread will not produce a visible image in area 153.

The present invention substantially obviates this problem by constructing the spreading assembly such that it spreads the processing composition in a thinner layer on the left side of the film's longitudinal axis 115 than on the right thereby increasing the area that can be covered by the processing composition on the left side. Specifically, this is accomplished by providing the left end portion 127 of roller 62 with a diameter less than that of intermediate section 130 (as best seen in FIG. 2a) and right end portion 129, the latter two having substantially the same diameters. As shown in FIG. 4, film unit engaging end portions 127 and 129 are adapted to cooperate with opposite end portions of roller 60 to engage the edge bindings 134 of the film unit thereby establishing a gap of predetermined thickness and configuration between the sheet-contacting surfaces 128 and 130 of rollers 60 and 62. Providing the left end portion 127 of roller 62 with a smaller diameter than that of right end portion 129 results in the left hand portion (as viewed in FIG. 4) of sheet-contacting surface 130 extending further into opening 48 in film unit 42 than the right hand portion of surface 130, thereby providing a gap between surfaces 128 and 130 having a longitudinally extending, asymmetrical configuration for spreading the processing composition in a layer having an asymmetrical thickness as measured transversely of the direction of movement of the film unit relative to the rollers. Stated another way, reducing the diameter of left end portion 127 allows the left end of roller 60 to move closer to the left end of roller 62, thereby resulting in roller 60 being slightly canted off its horizontal axis relative to the horizontal axis 131 of top roller 62 when a film unit is passing between the rollers. In practice, it has been found that where the diameter of sheet-contacting portion 130 of roller 62 has a diameter of approximately .250 inches, a diameter of approximately .2496 inches for left end portion 127 is sufficient to substantially obviate the aforementioned problem of incomplete coverage of the film unit's photosensitive layer by the processing composition. While the present invention, including all of its embodiments, provides for spreading the processing composition in a layer of non-uniform thickness, it should be realized that the depth or thickness of the layer of composition on each side of the film units longitudinal axis within the limits necessary to initiate development and form the desired photographic image. For example, in a film unit of the type described, the thickness of the layer of processing composition may be between .002 and .003 inches. Thinning out the thickness of the layer of processing composition on the left side of the film unit by approximately .0001 inch relative to the right side of the film unit is generally sufficient to obtain complete coverage of area 153.

Reference is now made to FIG. 5 wherein an alternative embodiment of the invention is depicted. In this embodiment roller 62' is similar to roller 62 except that the diameter of left end portion 127' is the same as that of sheet-contacting portion 130 and right end portion 129. The aforementioned problem of incomplete spreading of the processing composition is substantially obviated by asymmetrically biasing the rollers toward

each other. For example, it has been found that loading the left side of shaft 108 (as viewed in FIG. 2) with a spring load of 4.75 lbs. and the right side of the shaft with a load of 3.75 lbs. provides a spread which completely covers a picture area (defined by opening 48) of approximately 3.1 inches square when the pod contains 800 milligrams of processing composition. The asymmetrical biasing of shaft 108 and roller 60 is accomplished by originally forming the end 116 of spring 96 at an angle relative to end 118, as shown at 116' in FIG. 2, such that after assembly of the spreader assembly, the end of spring 96 having end 116 located in position 116' will be under greater compression than the opposite end of the spring, thereby providing a greater load on the end of shaft 108 which is closest to the drive side of the spreader assembly, i.e., the left side as viewed in FIGS. 2-6. As best seen in FIG. 5, when a film unit enters the bite of rollers 60 and 62', roller 60 is moved away from roller 62'. As the film unit enters between the rollers, the gap therebetween changes to an asymmetrical configuration with the minimum depth of the gap being on the left side of the roller assembly. Accordingly, when the rollers rupture pod 46, the processing composition 47 which was contained in the pod closest to the left side of the film unit is spread in a thinner layer across the photosensitive area, thereby enabling the composition to be spread over a greater area, i.e., the entire area defined by opening 48.

Reference is now made to FIG. 6 wherein still another embodiment of the invention is illustrated. In this embodiment the spreading assembly includes a top roller 62' and the bottom roller 60' mounted for rotation about parallel axes 131 and 133. Roller 60' is adapted to cooperate with roller 62' to define a longitudinally extending (from end-to-end of the rollers) asymmetrically configured gap therebetween when a film unit is located between the rollers. Specifically, roller 60' is provided with a "candlepin" configuration having a major diameter at 160 which gradually decreases to similar minor diameters near its ends 162 and 164. It should be noted that the major diameter 160 is located offcenter, i.e., it is closer to end 162 than end 164, thereby decreasing the thickness of the processing composition 47 on the left side of the spreading assembly relative to the right side. As in the previous embodiments, rollers 60' and 62' cooperate with each other to spread the processing composition across a photosensitive layer of the film unit in a layer having an asymmetrical thickness, as measured in a direction transverse to the direction of movement of the film relative to the rollers, with the minimum thickness of the layer being located on that side of the film which first enters the bite of the rollers.

Since certain changes may be made in the above apparatus without departing from the scope of the invention herein involved, it is intended that all matter contained in the above description or shown in the accompanying drawings shall be interpreted as illustrative and not in a limiting sense.

What is claimed is:

1. Photographic apparatus for spreading a processing composition across a photosensitive layer of an exposed film unit comprising:

pressure-applying means adapted to engage opposite sides of an exposed film unit for spreading a processing composition across a photosensitive layer

of the exposed film unit in a layer having an asymmetrical thickness, as measured in a plane transverse to the direction of movement of the film unit relative to said pressure-applying means, said pressure-applying means including means defining a longitudinally extending, asymmetrically configured gap when the film unit is being advanced therebetween, said gap tapering from a maximum thickness at one end to a minimum thickness at a point more than halfway toward its opposite end.

2. Photographic apparatus as defined in claim 1 wherein said opposite end of said gap is positioned to be engaged by a leading edge of the exposed film unit before or at the time that said one end of said gap is engaged by the leading end of the exposed film unit.

3. Photographic apparatus for spreading a processing composition across a photosensitive layer of an exposed film unit comprising:

pressure-applying means adapted to engage opposite sides of an exposed film unit for spreading a processing composition across a photosensitive layer of the exposed film unit in a layer having an asymmetrical thickness, as measured in a plane transverse to the direction of movement of the film unit relative to said pressure-applying means, said pressure-applying means including means defining a longitudinally extending, asymmetrically configured gap when the film unit is being advanced therebetween, said gap tapering from a maximum thickness at one end to a minimum thickness at a location less than one half of the distance between opposite ends of said gap.

4. Photographic apparatus as defined in claim 3 wherein said one end of said gap is adapted to be engaged by a leading edge of the exposed film unit at or after the time that the opposite end of said gap is engaged by the leading end of the film unit.

5. Photographic apparatus as defined in claim 4 wherein said pressure-applying means includes first and second rollers, said first roller having film unit engaging surfaces including first and second end portions and an intermediate portion having a maximum diameter non-uniformly spaced from said first and second end portions.

6. Photographic apparatus as defined in claim 5 wherein said second roller includes film unit engaging portions having similar diameters.

7. Photographic apparatus as defined in claim 6 wherein said film unit engaging portions of said second roller include an intermediate portion and first and second end portions, said second roller further including a recess located adjacent each end of said intermediate portion of said second roller and said first and second end portions of said second roller.

8. Photographic apparatus as defined in claim 7 further including means for establishing a predetermined minimum spacing between said first and second rollers.

9. Photographic apparatus as defined in claim 5 further including means for resiliently biasing one of said first and second rollers toward the other.

10. Photographic apparatus for spreading a processing composition across a photosensitive layer of an exposed film unit comprising:

pressure-applying means including a first roller having a longitudinally extending symmetrically con-

figured film engaging portion and a second roller having film unit engaging surfaces including first and second end portions, said first and second rollers being adapted to engage opposite sides of an exposed film unit for spreading a processing composition across a photosensitive layer of the exposed film unit in a layer having an asymmetrical thickness, as measured in a plane transverse to the direction of movement of the film unit relative to said pressure-applying means, said pressure-applying means defining a longitudinally extending, asymmetrically configured gap when the film unit is being advanced therebetween, said gap tapering from a maximum thickness at one end to a minimum thickness at a point more than halfway toward its opposite end, said opposite end of said gap being positioned to be engaged by a leading edge of the exposed film unit before or at the time that said one end of said gap is engaged by the leading end of the exposed film unit, said first end portion being located near said opposite end of said gap and having a diameter less than that of said second end portion.

11. Photographic apparatus as defined in claim 10 wherein said second roller includes an intermediate film unit engaging portion located between said first and second end portions, said intermediate film unit engaging portion having a diameter substantially the same as said second end portion.

12. Photographic apparatus as defined in claim 11 wherein said second roller further includes a recess located adjacent each end of said intermediate film unit engaging portion and between said first and second end portions.

13. Photographic apparatus as defined in claim 12 further including means for establishing a predetermined minimum spacing between said first and second rollers to facilitate the entry of the leading edge of the exposed film unit therebetween.

14. Photographic apparatus as defined in claim 10 further including means for resiliently biasing one of said said first and second rollers toward the other.

15. Photographic apparatus for spreading a processing composition in a layer between a pair of elements, at least one of which forms part of a film unit, said apparatus comprising:

pressure-applying means including first and second means adapted to define an elongated gap through which a film unit is adapted to be moved;
means for mounting said first and second means for relative movement toward and away from each other; and
means for applying an asymmetrical biasing force to one of said first and second means during spreading of a processing composition across a photosensitive layer of the film unit, whereby said first and second means spreads the processing composition in a layer of non-uniform thickness.

16. Photographic apparatus as defined in claim 15 wherein said first means is a roller assembly having opposite end portions and said biasing means is mounted for engagement with at least one of said end portions.

17. Photographic apparatus as defined in claim 16 wherein said biasing means is mounted for engagement with both of said end portions.

18. Photographic apparatus as defined in claim 17 wherein said biasing means is a torsion spring having opposite ends adapted to engage said end portions of said roller assembly.

19. Photographic apparatus as defined in claim 18 wherein said opposite end portions of said roller assembly comprise substantially non-rotatable portions of said roller assembly, whereby frictional losses between said opposite ends of said torsion spring and said opposite end portions of said roller assembly are substantially eliminated.

20. Photographic apparatus comprising:
means for supporting a film unit having a longitudinal axis in position for exposure;
means for engaging the film unit on one side of the longitudinal axis and moving the film unit out of the exposure position subsequent to exposure; and

pressure-applying means adapted to engage opposite sides of the exposed film unit for spreading a processing composition across a photosensitive layer thereof in a layer having an asymmetrical thickness, as measured in a plane transverse to the direction of movement of the exposed film unit relative to said pressure-applying means, said pressure-applying means including means defining a longitudinally extending, asymmetrically configured gap when the film unit is being advanced therebetween, said gap tapering from a maximum thickness at one end to a minimum thickness at a point more than halfway toward its opposite end.

21. Photographic apparatus as defined in claim 20 wherein said pressure-applying means includes first and second rollers.

22. Photographic apparatus as defined in claim 21 wherein said first roller includes a film unit engaging portion having a substantially longitudinally extending symmetrical configuration and said second roller includes film unit engaging portions of different diameters.

23. Photographic apparatus as defined in claim 22 further including means for biasing one of said first and second rollers toward the other.

24. Photographic apparatus as defined in claim 21 wherein said first roller includes a film unit engaging portion of candlepin configuration with its maximum diameter located closer to one end of said film unit engaging portion than to its opposite end and said second roller includes film unit engaging portions of substantially identical diameters.

25. Photographic apparatus as defined in claim 24 further including means for biasing one of said first and second rollers toward the other.

26. Photographic apparatus comprising:
means for supporting a film unit having a longitudinal axis in position for exposure;
means for engaging the film unit on one side of the longitudinal axis and moving the film unit out of the exposure position subsequent to exposure;
pressure-applying means mounted in position to receive the exposed film unit as it moves away from the exposure position, said pressure-applying means including first and second means adapted to define an elongated gap through which the film unit is adapted to be moved;

means for mounting said first and second means for relative movement toward and away from each other; and

means for applying an asymmetrically biasing force to one of said first and second means to spread a processing composition across a photosensitive layer of the film unit, said asymmetrical biasing force being greatest on the longitudinal side of the film unit engaged by said means for engaging, whereby said pressure-applying means spreads the processing composition in a layer of non-uniform thickness.

27. Photographic apparatus as defined in claim 26 wherein said first means is a roller assembly having opposite end portions and said biasing means is mounted for engagement with at least one of said end portions.

28. Photographic apparatus as defined in claim 27 wherein said biasing means is mounted for engagement with both of said end portions.

29. Photographic apparatus as defined in claim 28 wherein said biasing means is a torsion spring having opposite ends adapted to engage said end portions of said roller assembly.

30. Photographic apparatus as defined in claim 29 wherein said opposite end portions of said roller assembly comprise substantially non-rotatable portions of said roller assembly, whereby frictional losses between said opposite end of said torsion spring and said opposite end portions of said roller assembly are substantially eliminated.

31. Photographic apparatus for use with a film unit having leading and trailing edges interconnected by spaced side edges and a container of processing composition located adjacent the leading edge which is adapted to be ruptured prior to spreading the processing composition across a photosensitive layer of the film unit and toward the trailing edge, comprising:

means for locating the film unit in position for expo-

sure;

means for engaging the film unit at its trailing edge adjacent one of the side edges for applying a canting movement to the film unit as it is advanced out of the exposure position, subsequent to exposure; and

pressure-applying means for spreading the processing composition across the photosensitive layer in a layer having an asymmetrical thickness as measured in a plane transverse to the direction of movement of the exposed film unit relative to said pressure-applying means, said pressure-applying means including means adapted to define a longitudinally extending, asymmetrically configured gap when the film unit is being advanced therethrough.

32. Photographic apparatus as defined in claim 31 wherein said gap tapers from a maximum depth near one end to a minimum depth near its opposite end.

33. Photographic apparatus as defined in claim 32 wherein said opposite end of said gap is adapted to be engaged by a portion of the leading edge of the exposed film unit located adjacent the one side edge before or at the time that said one end of said gap is engaged by a portion of the leading edge of the exposed film unit located adjacent the other side edge of the exposed film unit.

34. Photographic apparatus as defined in claim 31 wherein said gap tapers from a maximum depth at one end to a minimum depth at a point more than halfway toward its opposite end.

35. Photographic apparatus as defined in claim 34 wherein said opposite end of said gap is adapted to be engaged by a portion of the leading edge of the exposed film unit located adjacent the one side edge before or at the time that a portion of the leading edge of the exposed film unit located adjacent the other side edge engages said one end of said gap.
